UNITED STATES PATENT OFFICE

ELMER C. SCHACHT, OF TROY, NEW YORK, ASSIGNOR TO BEHR-MANNING CORPORATION, OF TROY, NEW YORK, A CORPORATION OF NEW YORK

ABRADING DEVICE

Application filed June 25, 1927. Serial No. 201,437.

The present invention relates to abrading devices and more especially to improved means for attaching and securing an abrasive element to a revoluble supporting disc or the like.

An important feature of the invention is the provision of a rotatable supporting member with attaching wings adapted to enter slots or openings directed outwardly from the center of an abrasive disc, the free edges of the wings and the edges of the slots being angularly related, so that the wings gradually enter the slots of the disc upon relative rotation of the wings and disc. Carrying out this idea, the invention contemplates the provision of radially disposed slits or openings in the sanding disc cooperating with the free edges of the wings which are directed along lines at an angle to the radii of the supporting disc and sanding disc.

A further feature of the invention consists in providing an abrasive element or disc with a centrally disposed opening having cuts or slits extending towards the outer edge of the disc, one edge of each of the cuts being depressed or deflected to extend substantially parallel to the other edge and provide an opening of uniform width throughout a substantial portion of its length. The abrasive surface of each deflected edge of the slits has preferably a relatively smooth portion to facilitate the entry of the attaching instrumentalities carried by the supporting member.

Another feature of the invention is to provide a simple, inexpensive and efficient means for positively securing an abrasive element to a supporting disc, and which permits the abrasive element to be readily attached or removed from engagement with the supporting disc. Additionally, the parts are constructed so as to be easily assembled or disassembled for the purpose of replacing such of them as has become defective or worn out through usage.

Other objects and features of the invention will become apparent from the following description when taken in conjunction with the accompanying claims.

Referring to the drawing in which is dis-

closed a preferred embodiment of the development—

Figure 1 is a side elevation of an abrading machine with the invention applied thereto.

Figure 2 is a front view of Figure 1.

Figure 3 is a sectional view taken substantially along the line 3—3 of Figure 2.

Figure 4 is an enlarged front view of the supporting disc that carries the abrasive element.

Figure 5 is a fragmentary enlarged front view showing the initial position of the abrading element relative to the supporting disc.

Figure 6 is a sectional view taken substantially along the line 6—6 of Figure 2.

Figure 7 is a sectional view taken substantially along the line 7—7 of Figure 3.

Figure 8 is a sectional view of a portion of the disc taken along a line extending transversely of one of the radial slits, as illustrated by the line 8—8 of Figure 9.

Figure 9 is a sectional view of a portion of the disc along a line diametrical of the central opening and longitudinally of the radial slits, as illustrated by the line 9—9 of Figure 8.

Referring to the drawing, in which like numerals indicate like parts in the various views, 10 denotes the casing of an abrasive machine which is provided with a drive shaft 11 that may be actuated by any suitable drive mechanism, not shown. The shaft 11 terminates in a reduced threaded end 12 to which is secured the collar 14, which collar has a projecting stud 13 and an annular flange 15 surrounding the adjacent periphery of the shaft 11. A washer 16 may be interposed between the opposed faces of the collar 14 and the shaft 11.

A series of backing plate 17, 18 and 19 of progressively increasing diameters are preferably associated with the collar 14, and act as a support for a body 20, preferably of yieldable material, such as felt. This material may be secured to the backing 19 in any suitable manner, as by rivets 21, one of which is shown in Figure 6.

The stud 13 of the collar 14, has an external threaded surface 22 arranged to receive a

complementary portion 23 of a sleeve 24, which sleeve is preferably integral with carrying means, such as the supporting disc 25, for attaching wings 28 and 29. The back 5 supporting members 17, 18 and 19, and the disc 25 are preferably secured to the collar 14 by the rivets 26 (Fig. 6).

The outer face of the disc 25 is provided with a centering hub 27 and, outwardly from 10 the hub, attaching wings or blades 28 and 29 (Fig. 4). Each of these wings is preferably struck out or stamped from the disc 25, and has a free straight edge 30 which is formed at one end into a point 31 which, due to the dis- 15 position of the edge in other than a radial line, (in the present instance tangential to the hub) is disposed forwardly or in advance of the remainder of the edge. The edge 30 and point 31 are feathered or thinned (Fig. 20 7) so as to facilitate the entry of the wings in an abrasive element 32. The points 31 are also curled upwardly (Fig. 3) to facilitate entrance of the same into the openings in the sanding disc. It will be observed that the 25 edges 30 are offset relative to each other around the hub and extend along lines other than radial to the periphery of the hub 27, so that upon relative turning of the wings and an abrasive disc, the points of the wings 30 will first enter radial openings or slits in the abrasive disc.

The abrasive element 32 is preferably in the form of a sheet or disc, and may assume any suitable configuration as may be found 35 desirable or expedient. By the term "disc" as used in the specification, is meant any abrasive element, irrespective of its form. The abrasive disc 32 has a central opening 33 of slightly larger diameter than the hub 27, 40 arranged to receive the hub when the disc is mounted on the rotatable head. Extending radially toward the disc margin, and in the present instance communicating with the central opening 33 of the abrasive disc, are the 45 cuts, slits, or openings 34 and 35 (Fig. 5), which are disposed on substantially diametrically opposite sides of the hub 27, and are arranged to receive the wings 28 and 29 of the supporting disc 25. As will be understood, 50 the relative disposition of the free edges 30 on the wings and the complementary slits or openings in the sanding disc cause the edges of the wings gradually to enter the slits as the sanding disc and wings are relatively rotated. In other words, the entering edges of 55 the wings are disposed on other than radial lines, whereas the complementary openings or slits in the disc are radially directed. Obviously the invention is not limited to this 60 precise arrangement, the essence of this feature being a relative arrangement which will effect the result desired.

In order to facilitate the entry of the free edges 30 and the pointed ends 31 of the wings 65 28 and 29 into the cuts 34 and 35, the abrasive

surface of one edge of each of these cuts is de- 70 pressed or deflected downwardly as at 36 (Fig. 8), and the abrasive surface smoothed or removed therefrom so as to provide a relatively plane portion 37.

Each of the openings or slits 34, 35 has its deflected edge 36 so disposed that its edge ex- 75 tends substantially parallel to non-deflected opposed edge 38 of the slit (Fig. 8), thus providing an opening 39 of substantially uni- 80 form width throughout a major portion of its length which together with the smooth surface 37 materially facilitates the introduction of the wings 28 and 29 into engagement with the abrasive element 32.

The abrasive element 32 may be attached and firmly secured to the disc 25 by first stop- 85 ping the rotation of the drive shaft 11 and applying the abrasive element 32 so that the slits 34 and 35 will register with the pointed ends of the wings 28 and 29 respectively. The abrasive disc 32 is then revolved in the direction shown by the arrow in Figure 5, until the wings 28 and 29 have passed completely through the slits 34 and 35 and the 90 parts are in the position shown in Figure 2, when the abrasive element will then be firmly secured in position. Conversely, when it is desired to remove the abrasive element from the supporting disc 25 this may be readily ef- 95 fected by rotating the abrasive element on the disc in a counter-clockwise direction.

The supporting head or body 20 has a central opening 20' in which is positioned the disc 25 so that when the parts are as- 100 sembled, as shown in Figures 3 and 6, the disc 25 and the wings 28 and 29 will be below the plane of the operative portion of the abrasive surface which is disposed radially outwardly from the wings.

This depressed arrangement of the disc and wings does not make it inconvenient to attach the abrasive element due to the fact that the latter is formed with the downwardly deflected edges 36, which readily fit be- 105 neath the wings upon relative rotation of the abrasive disc and wings, notwithstanding the fact that the wings are below the plane of the remainder of the disc. The depressed position of the wings is desirable 110 to avoid contact of the same with the object to which the abrasive element is applied.

As the machine may be readily assembled or disassembled, and since the essential ele- 115 ments thereof can be separately manufac- 120 tured, it will be seen that should any of the parts need to be replaced, the same may be economically effected without requiring the renewal of the other parts. Moreover, due to the particular attaching means employed, 125 abrasive elements of various kinds and types can be used with the machine, depending upon the work to be done.

It is to be understood that the form of the invention herewith shown and described 130

is merely illustrative of a preferred embodiment of the development, and that such changes as fall within the purview of one skilled in the art may be made without departing from the spirit of the invention and the scope of the appended claims.

What I claim is:

1. A substantially flexible abrasive element of the class described, having a central opening and openings disposed outwardly of the central opening, one edge of each of the outwardly disposed openings being depressed and the abrasive surface adjacent the same being relatively smooth.
- 10 2. An abrasive element of the class described, comprising a substantially yieldable disc having a central opening and an opening disposed outwardly therefrom, the outwardly disposed opening having one edge depressed and the abrasive surface adjacent the same being relatively smooth, said depression being such as to provide an opening of uniform width throughout a substantial portion of the length thereof.
- 20 3. A disc of the class described having an abrasive surface, said disc being formed with a central opening and outwardly extending openings on substantially opposite sides of the central opening, one edge of the abrasive surface adjacent each of the outwardly extending openings having a depressed relatively smooth portion.
- 25 4. A disc of the class described having an abrasive surface, said disc being formed with a central opening and slits disposed outwardly of the central opening and communicating therewith, one edge of the abrasive surface adjacent each of the slits being depressed a uniform distance through a substantial portion of the slit whereby to form an opening of uniform width.
- 30 5. As a new article of manufacture, a disc having an abrasive surface and a substantially central opening, said disc being cut in a direction towards the outer edge of the disc from said opening, one edge of said cut being deflected from the plane of the other edge and having a substantial portion thereof paralleling said other edge whereby to provide an opening between said edges of substantially uniform width.
- 35 6. As a new article of manufacture, a disc having an abrasive surface and a substantially central opening, said disc being cut in a direction towards the outer edge of the disc from said opening, one edge of said cut being deflected from the plane of its other edge and having a substantial portion thereof paralleling said other edge whereby to provide an opening between said edges of substantially uniform width, the deflected edge being relatively smooth.
- 40 7. A device of the class described comprising a revoluble supporting disc having a centering hub and wings located outwardly

thereof, each of said wings having a free edge forming at one end with an adjacent edge a point disposed forwardly of the remainder of the edge in a direction circumferentially of the disc.

8. A device of the class described comprising a revoluble supporting disc having a centering hub and wings located outwardly thereof, each of said wings having a free, substantially straight edge forming at one end with an adjacent edge a point disposed forwardly of the remainder of the edge in a direction circumferentially of the disc.

9. A device of the class described comprising a revoluble supporting disc having a centering hub and wings located outwardly thereof, each of said wings having a free edge forming with an adjacent edge at one end a point disposed forwardly of the remainder of the edge, said edge being disposed at an angle to the radii of said disc.

10. A device of the class described comprising a revoluble supporting disc having a centering hub and wings located outwardly thereof, each of said wings having a free edge terminating at its inner end in a point disposed forwardly of the remainder of the edge in a direction circumferentially of the disc.

11. In a device of the class described comprising a revoluble support having a centering hub and wings outwardly thereof each having a free edge formed with an adjacent edge into a point adapted to enter initially into a complementary opening in an abrasive disc, and an abrasive disc having a hub receiving opening and an opening complementary to each wing, said wing free edge and said complementary openings, when said disc and support are assembled, one extending substantially radially with respect to said hub and the other at an angle thereto whereby to cause gradual entry of the ends of the wings into said openings upon relative rotation of the wings and disc.

12. In a device of the class described, a revoluble support having a centering hub and wings outwardly thereof, each having a free edge formed with an adjacent edge at the inner end of the free edge into a point adapted to enter initially into a complementary opening in an abrasive disc, and an abrasive disc having a hub receiving opening and an opening complementary to each wing, said wing free edge and said complementary disc openings, when said disc and support are assembled, one extending substantially radially with respect to said hub and the other at an angle thereto whereby to cause gradual entry of the ends of the wings into said openings upon relative rotation of the wings and disc.

13. In a device of the class described, a revoluble support having a centering hub and wings outwardly thereof, each wing having a free edge formed with an adjacent edge

into a point, said point being disposed in advance of the remainder of said edge around the hub and the edge being directed at an angle to a radial line extending from the hub, 5 and an abrasive disc having an opening to receive said hub and substantially radially extending openings each complementary to one of said wings whereby to gradually receive the edges of said wings upon relative rotation of the wings and discs.

10 14. In a device of the class described, a revoluble support having a centering hub and wings outwardly thereof, each wing having a substantially straight free edge formed at its inner end into a point, said point being disposed in advance of the remainder of said edge around the hub and the edge being directed at an angle to a radial line extending from the hub, and an abrasive disc having an 15 opening to receive said hub and substantially radially extending openings each complementary to one of said wings whereby to gradually receive the edges of said wings upon relative rotation of the wings and disc.

20 15. An abrasive disc having a central opening and slits extending outwardly therefrom, one edge of certain of said slits being depressed but having a substantial part of the depressed portion maintained in parallelism 25 with the other edge.

30 16. An abrasive disc having a central opening and slits extending outwardly therefrom, one edge of certain of said slits having the abrasive surface adjacent the same relatively 35 smoothed.

In testimony whereof I have hereunto set my hand.

ELMER C. SCHACHT.
